UNITED STATES PATENT OFFICE.

JACOB LUSTENBERGER, OF ST. JOSEPH, MISSOURI.

WASHING-MACHINE.

1,134,471.

Specification of Letters Patent. Patented Apr. 6, 1915.

Application filed June 21, 1912. Serial No. 704,976.

To all whom it may concern:

Be it known that I, JACOB LUSTENBERGER, a citizen of the United States, residing at St. Joseph, in the county of Buchanan and State of Missouri, have invented certain new and useful Improvements in Washing-Machines, of which the following is a specification, reference being had therein to the accompanying drawing.

My invention relates to improvements in washing machines of that class in which the rubber shaft is rotated in alternate directions and longitudinally moved at the same time.

The objects of my improvements are to provide a simple, substantial and durable machine of this class, which shall be highly efficient, and extremely cheap in cost of manufacture, and in which frictional resistance to the movement of the moving parts has been reduced to the minimum. I attain these objects by the mechanism illustrated in the accompanying drawing, in which:—

Figure 1 is a side elevation of the machine, certain parts being in section, to avoid obscurity; the moving parts being shown at the lowest point of their movement. Fig. 2 is a top plan, showing the parts at a higher point of their movement. Fig. 3 is an enlarged transverse section of the moving parts, on the line X-X, seen in Fig. 1. Fig. 4 is a horizontal section on the line Y-Y, seen in Fig. 3. Fig. 5 is an enlarged edge view, in detail, of one of the toggle bars. Fig. 6 is a side elevation of one of the other various forms in which the machine may be constructed.

Referring to Fig. 1, tub 1 may be formed as shown, or may be of any other form, suitable to hold suds, not shown. The interior surface of said tub, may be either smooth or corrugated, as desired. Said tub is provided with bottom 2 and cover 3. The latter has a large square opening 3' formed therethrough. Said opening is closed by lid 4, hinged at one of its edges, on said cover by hinges 4', and has its free edge detachably secured to said cover by turn buttons 4'', seen in Fig. 2. Frame 5 has frame base 5' formed therewith, said base being rigidly secured on lid 4. Said base, the upper portion of said frame and said lid, each have an aperture formed through the central portion thereof. Vertical rubber shaft 6 is passed through said apertures, and is rotat-

ably and slidably mounted therein, as hereinafter described. Said shaft has notches 6' formed in one of its edges. Referring to Figs. 3 and 4, said shaft is preferably formed of an X shaped metal bar and has cross head 7 clamped thereon by clamp 8. Said clamp has clamp projections 8' formed on its inner surface, which engage notches 6' for adjustably holding shaft 6, at any desired height. One of the ends of said clamp is detachably secured to cross head 7 by clamp hook 8'' formed with said clamp and passed through an aperture in said cross head, while the other end of said clamp is secured to said cross head by thumb screw 9, passed loosely through said clamp and screwed into cross head 7.

Referring to Fig. 3, sleeve 7' is formed with cross head 7 and extends therefrom, loosely through the previously mentioned apertures in base 5' and lid 4, for slidably and rotatably guiding the lower end portion of shaft 6. The upper end of said shaft passes through and is slidably guided by journal piece 10, rotatably mounted in the previously mentioned aperture through the upper portion of frame 5. Said journal piece is held in place by the upper end of spiral spring 11, the lower end of which presses upon and is supported by cross head 7. Referring to Fig. 4, each of the two ends of said cross head has a ball 7'' formed therewith, and provided with ball jointed supporting means therefor, since they are both alike in construction and operation, a detailed description of one is sufficient.

Referring to Fig. 5, toggle bar 12 is formed of separable halves secured together by bolts and nuts 12'. Said bar has a socket 12'' formed in each end thereof. Said sockets are adapted to interchangeably fit on ball 7'' and bearing ball 13, the latter being provided with stem 13' formed therewith. Said stem is secured in frame 5 as seen in Fig. 1. Cross arm ball 7'' is held in one of said sockets, while the other socket embraces bearing ball 13, thus providing ball jointed supporting means for cross arm 7 as previously mentioned. Drive block 14 has rose face 14' formed on one side thereof. Said block is secured on the X shaped reduced portion 6'' of shaft 6, by nut 15 screwed on the farther reduced and threaded portion 6' of shaft 6. Crank 16 has rose face 16' formed on the inner end portion thereof and spherically shaped handle 16''

mounted on the outer end of said crank. Rose face 16' is secured in engagement with rose face 14', by thumb screw 17 passed loosely through said crank at the center of 5 said rose face 16' and screwed into drive block 14 at the center of face 14', for adjustably securing said crank on said block with handle 16" at any desired height. On the lower end of shaft 6, is secured the rubber disk 18, having apertures 18' formed therethrough. Rubbers 19 are secured on the lower surface of said disk, and may be either four in number, as shown, or may be of any other plurality in number, arranged 10 15 radially on the lower surface of said disk.

In preparing the machine for operation, (the parts being in position seen in Fig. 2,) thumb buttons 4" are rotated from over lid 4, after which said lid is rotated on hinges 20 25 30 35 40 45 50 55 4' from cover 3. Suds and fabric, not shown, are passed through opening 3' into tub 1 after which the parts are returned to the position shown in Fig. 2. The operator with one hand grasps handle 16" and moves it to a point near point B, then with the other hand he loosens thumb screw 9 and draws the thus loosened end of clamp 8 from shaft 6, until clamp projections 8' are disengaged from notches 6', upon which said shaft and the thereto attached parts gravitate until rubbers 19 rest upon said fabric. Said operator returns cap 8 to its position shown, with projection 8' in notches 6' and tightens thumb screw 9, after which the machine is ready for operation. Should handle 16" be at such height as is uncomfortable for said operation, the same is adjusted to proper height by loosening thumb screw 17, forcing said handle to the desired height and tightening said screw. In operation said operator reciprocatively moves handle 16" between points A and C, seen in Fig. 2. When said handle passes point B the parts are at their lowest point of movement, as seen in Fig. 1, at which point rubbers 19 and rubber disk 18 are firmly pressed upon said fabric. At the same juncture, said suds escapes from said fabric, through apertures 18" as indicated by dotted lines. As said handle is moved from point B, in either direction, the lower ends of toggle bars 12 are moved from the position seen in Fig. 1 to a higher position seen in Fig. 2, and describe a spiral, upwardly inclined arc. This movement of said toggle bars 12, carries cross head 7 and its attached parts, to said higher position. Said upward movement of said

part continues so long as handle 16" is moved from point B, in either direction, until the limit of said movement is reached. 60 The upward movement of said cross head compresses spring 11, which elastically presses upon said cross head and accelerates the movement of same. From the foregoing it will be understood that rubbers 19 and 65 rubber disk 18 are rotated reciprocatively and moved upward and downward at the same time. This movement of said parts, thoroughly rubs and agitates said fabric in said suds, which together with the previously described forcing of said suds from said fabric, thoroughly cleanses the latter. After said cleansing operation is fully performed, said suds is drawn from tub 1, through plugged aperture 20, in the usual 70 75 manner.

While I have shown and described my invention in the foregoing manner, with toggle bars 12 depending from bearing balls 13, and with spring 11 and journal piece 10 80 above said cross head it is evident that said parts could be placed in transposed position, as seen in Fig. 6, with sleeve 7' shortened as seen at 7" and journal piece 10' secured in frame 5 by set screw 10".

Having fully described my invention, what I claim as new, and desire to secure by Letters Patent is:—

The combination with a tub provided with a lid thereon, of a frame securely mounted 90 on said lid; an agitator shaft having its upper end portion rotatably and slidably mounted in the upper portion of said frame the lower end portion of said shaft being extended through said lid into said tub; an 95 agitator secured on the lower end of said shaft; a cross-head adjustably secured on said shaft above said lid; a guide sleeve formed with said cross-head said sleeve passing loosely through said lid and encircling 100 said shaft to laterally guide the lower end portion of said shaft; means whereby said shaft is rotated in alternate directions; and link connecting means whereby the ends of said cross-head are connected with said 105 frame for raising and lowering said shaft when the same is rotated.

In testimony whereof I affix my signature in the presence of two witnesses.

JACOB LUSTENBERGER.
